ATTORNEYS

UNITED STATES PATENT OFFICE.

ABRAHAM FOX, OF NEW YORK, N. Y., ASSIGNOR TO THE PATRICIA PETTICOAT COMPANY, OF NEW YORK, N. Y., A CORPORATION OF NEW YORK.

SLIP.

Application filed October 1, 1925. Serial No. 59,884.

This invention relates to slips and more particularly to a garment especially adapted for use by girls and women, and while I refer to the same as a slip I would have it distinctly understood that I desire to cover the garment broadly whether it be worn as a slip, as an outer garment, or as an under-garment or analogous use.

An object of my invention is to provide a slip of improved construction whereby a slash is provided in the back and lower portion of the garment to give freedom to the legs in walking or to the body and legs while the wearer is in a sitting posture.

15 A further object is to provide an improved construction of slip which has straight lines but which gives the desired freedom in the lower portion of the garment without exposure.

20 With these and other objects in view, the invention consists in certain novel features of construction and combinations and arrangements of parts, which will be more fully hereinafter described and pointed out in the claim.

In the accompanying drawings—

Figure 1 is a perspective view, taken from the front, illustrating my improved slip in position on the wearer;

30 Figure 2 is a similar view taken from the rear;

Figure 3 is a view in transverse section of the garment on the line 3—3 of Figure 1;

Figure 4 is a similar view in section on the line 4—4 of Figure 1;

35 Figure 5 is an exaggerated view in section on the line 5—5 of Figure 2.

My improved slip is preferably formed of three pieces, namely, a front piece 1 and 40 two back pieces 2 and 3. Suitable shoulder straps 4 may be provided or other means may be employed for supporting the garment on the wearer.

45 The front piece 1 is preferably of the full width of the garment and is secured along its edges to the back pieces 2 and 3, respectively, as shown at 5.

50 The back piece 3 constitutes a piece having relatively straight lines extending throughout the length of the garment, while the piece 2 is relatively narrow from the top of the garment to a point 6 intermediate the ends of the garment, and from this point 6 to the bottom of the garment is appreciably 55 wider.

The upper narrow portion 7 of the back piece 2 is joined to the edge of the back piece 3, as shown at 8, and from the point 6 extends transversely of the garment, and is also joined to the back piece by a line of stitching or other suitable connecting means, as indicated at 9.

The inner edge of piece 2 is free from attachment to the back piece 3 so that the back piece 3 from the point 6 to the bottom of the garment and the back piece 2 from the line of stitching 9 to the bottom of the garment are free from attachment and an open slash is thereby provided with a sufficient overlap provided by the wider lower portion back 70 piece or section 2, so that while the garment permits an expansion at its lower portion for freedom in walking or other movement of the legs or body, a sufficient overlap of the material is had to compel the garment to 75 remain smooth and unrumpled and also prevent exposure when in use.

It is of course to be understood that I may employ any desired material, that I may connect the several parts by any well known 80 expedient for joining the materials, and that I do not limit myself to the exact proportions nor to the various details of construction but consider myself at liberty to make such slight changes and alterations as fairly 85 fall within the spirit and scope of the appended claim.

I claim:

A slip of substantially uniform width throughout its length and comprising a 90 single front piece and a pair of back pieces, both of the latter joined to the front piece at the respective longitudinal edges thereof, one of said back pieces having substantially 95 parallel edges throughout its length and comprising more than half of the width of the back of the slip, the other back piece being of two different widths, the narrower width being at the upper portion of the slip and secured at its edge to the edge of the 100 other back piece, the wider portion of the last-mentioned back piece being secured to the other back piece at its upper end only whereby an overlapping portion is provided throughout the lower portion of the garment 105 intermediate the side edges thereof, said overlapping portion being open, constituting a slash.

ABRAHAM FOX.
